UNITED STATES PATENT OFFICE.

HENRY S. WOODRUFF, OF EAST ORANGE, NEW JERSEY, AND JAMES G. MOTLEY, OF NEW YORK, N. Y., ASSIGNORS TO WESTERN ELECTRIC COMPANY, INCORPORATED, OF NEW YORK, N. Y., A CORPORATION OF NEW YORK.

CALLING DIAL.

Application filed December 27, 1922. Serial No. 609,226.

To all whom it may concern:

Be it known that we, HENRY S. WOODRUFF and JAMES G. MOTLEY, citizens of the United States, residing at East Orange, in the county of Essex, State of New Jersey, and New York, in the county of Bronx, State of New York, respectively, have invented certain new and useful Improvements in Calling Dials, of which the following is a full, clear, concise, and exact description.

This invention relates to calling dials for automatic telephones and its object is to provide a simple and accurate dial of the non-reverting type.

In accordance with the general features of this invention there is provided a finger wheel adapted to operate through a motor mechanism which controls the pulsing mechanism through the medium of planetary gear members and rotating discs. The operation of this mechanism is controlled by a double locking bar by which either the finger wheel or the pulsing cam and its associated mechanism is locked against rotation. These members are so arranged that they may be enclosed in casing members which will completely protect the mechanism from dust.

Fig. 1 is a cross sectional side view of the dial.

Fig. 2 is a front view thereof.

Fig. 3 is a cross-sectional view of the dial across the line 3—3 in Fig. 1, from above showing portions of the pulsing mechanism.

Fig. 4 is a cross-sectional view across the line 4—4.

Fig. 5 is a cross section view across the line 5—5.

Fig. 6 is a view of a portion of a dial showing the locking bar complete.

The dial mechanism is completely enclosed by upper and lower casing members 4 and 5 and by a finger wheel 6 having finger holds 7 therein through which projections 9 on the top of a hollow shaft 10 protrude. The finger wheel is locked in place by means of an annular threaded member 11 which is screwed about the top of the projections 9. Above member 11 and the center of the finger wheel is an instruction card 8 held in an instruction card holder 12 having an extension 13 which serves to fasten it to the casing 4 and which acts as a finger stop at 14. The instruction card holder 12 is

attached to finger wheel 6 by means of a stud 15. The finger wheel has twelve finger holds 16 therein through ten of which can be seen numbers from one to zero upon a number plate 17 set upon a circular ledge on casing member 4. Rigidly attached to shaft 10 is a twelve toothed disc 18 and an internal gear 19. Running from the center of the dial and rotatably mounted in the casing member 5, and in the base of the shaft 10, is a rod 20 upon which a small external gear 21 is formed in the same plane with the internal gear 19. Between these gears is set a planetary gear 23 to which is fastened a restoring cam 24 formed about rod 20 and rotatably mounted thereon. The inner end of a motor spring 25 is attached to cam 24. Rigidly fastened to rod 20 are a stop cam 28 and a pulsing cam 29 which upon each rotation causes contact between impulse springs 30 and 31 to transmit impulses to the line. A centrifugal governor 32 is fastened at the upper end of rod 20 within shaft 10 directly under instruction card 8. The governor by being placed in the top instead of in the base of the dial, may be adjusted without removing the dial from the apparatus to which it is attached.

A double-locking bar 34 is pivoted on a rod 35 and has at one end an extension 36 to lock toothed disc 18 and finger wheel 6 against rotation, besides a release lever 37 operated by restoring cam 24; and at the other end, an extension 38 for locking stop cam 28. A pawl 39 is also pivoted on rod 35, and acts to allow the movement of the twelve toothed disc 18 in one direction, and to move the stop mechanism when the disc 18 moves in the other direction. Shunt springs 40, 41 and 42 operated by extension 38 are provided to cut out the receiver and to short circuit the transmitter by means of springs 31 and 32 when the pulsing cam 28 is in motion and at other times to connect the voice carrying mechanism in the line circuit.

The described mechanism operates as follows:

Suppose that it is desired to dial number 8. The user inserts his finger in the finger hold in finger wheel 6 over numeral 8 on the number plate 17, and revolves the finger wheel until his finger touches the finger stop 14. The shaft 10 and toothed disc 18 re-

olve with the finger wheel, eight teeth of the disc slipping past pawl 39. The internal gear also rotates, revolving the planetary gear 23 about gear 21 which is held motionless by extension 38 on bar 34 which locks cam 28 and hence rod 20 against rotation. As gear 23 revolves, it rotates the restoring cam 24 and winds spring 25 so that when the finger wheel is released the spring reverses the motion of gear 23, internal gear 19 and toothed disc 18. A short return motion of disc 18 operates pawl 39 to shift locking bar 34, moving extensions 36 and 37 inwardly and extension 38 outwardly. Toothed disc 18, to which internal gear 19 is affixed, is thus locked against rotation by extension 36, while extension 38 releases stop cam 28 so as to allow pulsing cam 29 and rod 20 carrying a small external gear 21 to rotate. By the same motion, extension 38 allows shunt spring 40 to form contact with spring 42 so that impulses may be sent over the line without the transmitter resistance being included. As soon as external gear 21 is allowed to rotate, the tension of spring 25 on restoring cam 24 and planetary gear 23 causes the rotation of gear 21 and rod 20, together with the governor and cam members affixed to the rod. The gear train is so designed that a full revolution of the finger wheel, which has twelve openings therein, in one direction will rotate restoring cam 24 and its associated gear and spring sufficiently to cause twelve revolutions of rod 20 in the other direction. Thus when number 8 is dialed, rod 20 and pulsing cam 29 will make eight revolutions before the return of restoring cam 24 to its original position. At each revolution of cam 29 contact is formed between springs 30 and 31 and an impulse is sent over the line, so that during the operation just described eight impulses are transmitted before restoring cam 24 returns to its first position, at which time its cammed edge bears against the end of extension 37 of bar 34 and forces it outwardly so that extension 38 is forced inwardly, locking the stop cam 28 against further revolution and moving spring 40 inwardly so as to form a contact with spring 41 to allow the ordinary operation of the telephone. By the same movement, extension 36 is carried outwardly along with extension 37, so that the finger wheel and its attached mechanism is again free to be rotated.

The invention claimed is:

1. In a calling dial, a finger wheel, a motor spring tensioned by the rotation of the finger wheel, a pulsing cam actuated by said spring, a pair of impulse contacts operated by said cam and a member for automatically locking the pulsing cam against rotation during the movement of the finger wheel and for locking the finger wheel

against rotation during the operation of said impulse contacts.

2. In a calling dial, a finger wheel, a toothed disc rotated thereby, an annular gear carried by said disc, a motor spring, a planetary gear mechanism operable through the movement of said annular gear to tension the motor spring, a pulsing cam actuated by the motor spring through the medium of the planetary gear mechanism, impulse contacts operable through the movement of said cam and a locking bar actuated by a slight backward rotation of the finger wheel for locking the pulsing cam against rotation during the movement of the finger wheel and for locking said finger wheel against rotation during the operation of the pulsing cam for operating said contacts.

3. In a calling dial, a finger wheel, a toothed disc, an internal gear rotating therewith, a pinion centrally disposed with reference to said gear, a planetary gear rotatable about said pinion and within said internal gear, a motor spring, means operated by the planetary gear for tensioning said spring, a pulsing cam secured to said pinion, an impulse contact in operative relation to said cam, and automatic means for locking the impulse cam against rotation during the movement of said finger wheel and for locking said finger wheel against rotation during the operation of said pulsing cam for operating said impulse contact.

4. In a calling dial, a casing, a finger wheel, a combined finger stop and instruction card holder attached to said casing, a sleeve affixed to the finger wheel, a motor spring tensioned by the rotation of the finger wheel, a pulsing cam actuated by said spring, contacts operable through the movement of said cam, a centrifugal governor arranged in said sleeve and rotatable therein for governing the speed of said cam, and automatic locking means for alternately locking and releasing said finger wheel and said cam for operating said contacts.

5. In a calling dial, a finger wheel, a motor spring, means operable through the movement of said wheel for winding said spring, said means including a planetary gear and a plate for supporting said gear, an impulse mechanism responsive to the tension of said spring, a speed governor for said mechanism, and means for holding said impulse mechanism during the movement of the finger wheel in one direction and for releasing said mechanism when the finger wheel has moved a small angular distance in the opposite direction.

6. In a calling dial, a finger wheel, a sleeve carried by said wheel, an annular gear, a toothed disc arranged on said sleeve and rotatable therewith, a shaft centrally disposed with reference to said gear, a pinion, an impulse cam arranged on said shaft,

contacts associated with said cam, a planetary gear for operatively connecting said pinion to said annular gear, a motor spring wound through the movement of said planetary gear for actuating said impulse wheel and a speed governor for controlling the movement of said impulse wheel for causing the operation of said contacts at a predetermined rate of speed.

5 10 7. In a calling dial, a finger wheel, a motor spring wound through the movement of said finger wheel, impulse contacts, a cam for operating said contacts, a planetary gear mechanism for operatively connecting

said finger wheel to said cam, said planetary gear mechanism being movable alternately with said cam and said finger wheel, and means for holding said cam stationary during the movement of said finger wheel in one direction and for locking said finger wheel during the movement of said cam for operating said contacts.

In witness whereof, we hereunto subscribe our names this 22nd day of December, A. D. 1922.

HENRY S. WOODRUFF.
JAMES G. MOTLEY.
